(57) **CLAIM**

I claim the ornamental design for a fishing lure, as shown and described.

DESCRIPTION

FIG. 1 is a front, bottom perspective view of a fishing lure; FIG. 2 is a front elevational view thereof; FIG. 3 is a rear elevational view thereof; FIG. 4 is a left side elevational view thereof; FIG. 5 is a right side elevational view thereof; FIG. 6 is a top plan view thereof; FIG. 7 is a bottom plan view thereof; and, FIG. 8 is a front, top perspective view thereof.

The broken line showing of environment in the drawings is included for the purpose of illustrating only and forms no part of the claimed design.
